United States Patent Office

Des. 229,525

Patented Dec. 11, 1973

229,525

HAT

Gary Kiyoshi Kobashikawa, 3460 Maluhia St.,
Honolulu, Hawaii 96816

Continuation of abandoned design application Ser. No.
161,402, July 12, 1971. This application Nov. 30, 1972,
Ser. No. 310,841

Term of patent 14 years

Int. Cl. D2—03

U.S. Cl. D2—250

FIG. 1

FIG. 2

FIG. 3

FIG. 4

FIG. 5

FIG. 6

FIG.7

FIG.8

FIG. 1 is a front perspective view of a hat showing a first embodiment of my new design;

FIG. 2 is a top plan view thereof;

FIG. 3 is an elevational view taken from the lower left of FIG. 1;

FIG. 4 is an elevational view taken from the lower right side of FIG. 1;

FIG. 5 is an elevational view taken from the right of FIG. 1;

FIG. 6 is an elevational view taken from the rear of FIG. 1;

FIG. 7 is a perspective view of a second embodiment of a hat showing my new design; and

FIG. 8 is a top plan view thereof.

This is a continuation-in-part of my copending application D-161,402 filed July 12, 1971 and now abandoned.

I claim:

The ornamental design for a hat, as shown and described.
